EARTH MOVING AND VEHICLE PROPELLING
CONVEYER FOR SELF-LOADING ROAD
BUILDING MACHINES

Hans R. Miller, Cross Lake, Minn.

Application February 24, 1947, Serial No. 730,250

3 Claims. (Cl. 37—7)

1

This invention relates to earth moving and road building machinery and is an improvement on the inventions disclosed in my two United States Letters Patent, Numbers 1,827,897, issued October 20, 1931, and 1,942,034, issued January 2, 1934. In my said patents, I disclosed machinery for cutting, collecting, removing and distributing dirt and other material under the control of the operator or driver. The said machines were propelled, preferably, by their own power and did the combined work of steam or power shovels, elevator graders, dump wagons and bulldozers, thereby materially economizing upon the machinery and equipment necessary for building and maintaining roads, leveling and filling building sites and the like.

It is an object of my present invention to materially simplify and improve upon the structures of my prior patents, providing a machine having even a greater capacity for work although more compact in form and utilizing preferably the full width and the full length of the chassis of a vehicle for cutting and loading dirt as well as accumulating the load.

A further object is the provision of a highly efficient earth moving and road building machine adapted to cut and collect earth over the entire width of the machine and to accumulate on the collecting body thereof, a deep stratum of material throughout the entire length and width of the machine.

Another object is the provision of a machine of the class described wherein the machine in vehicle form, is self-propelled and the body thereof occupies at least the full width and length of the chassis and is adapted to receive plowed or cut earth from the full width of the front end thereof and to selectively and at will, discharge and distribute material progressively from the rear end and if desired, also from the front, whereby the machine rarely needs to be turned for picking up a load and has traction-supporting means adapted to engage the ground below the level of the material being cut or plowed when moved in one direction and adapted to be supported on material progressively discharged, when moved in the opposite direction.

Another object is the provision in a machine of the class described, of efficient control and adjustment mechanism which will enable the driver or operator to conveniently and instantly control the guiding of the machine as well as the progressive loading and distributing of the material.

A still further object is the provision of a

2

thoroughly practical, large-capacity earth cutting and moving machine which will uniformly cut and progressively collect a stratum of earth, accumulating a very large-capacity load and adapted to progressively dump and distribute the load at will and at a desired rate of speed, in accordance with a wide variety of working conditions, thereby taking the place of several carry-all scrapers, a tractor-type pusher, a bulldozer and planers and an elevator grader.

These and other objects and advantages of my invention will be more apparent from the following description made in connection with the accompanying drawings, wherein like reference characters refer to similar parts throughout the several views and in which:

Fig. 1 is a plan view of an embodiment of my invention with some portions broken away;

Fig. 2 is a vertical section taken longitudinally through the machine on approximately the line 2—2 of Fig. 1;

Fig. 3 is a rear elevation of the machine with some portions broken away;

Fig. 4 is a cross section taken on the line 4—4 of Fig. 2; and

Fig. 5 is a vertical section taken longitudinally through the forward end of a somewhat different embodiment of the invention.

Chassis and tracks

In the form illustrated, my road building machine is supported at its medial and rear portions upon two sets of widely spaced traction members of the endless track type indicated as an entirety by the letter T. The frame for the two sets of tracks includes a pair of very heavy side channel members 7 disposed at the respective sides of the machine adjacent the ground and connected with the load-accumulating body for supporting the rear portion thereof by suitable means. The track frame includes also a heavy, horizontal platform 8 (see Fig. 3) for underlying the rear portion of the load-accumulating body and rigidly connected with the heavy, longitudinal frame members 9 of the body. Platform 8 at its medial portion has a depending bolster 8a forming at its lower portion, a heavy mounting for a large common rear axle 10 of the two sets of tracks.

The forward ends of the side channel track members 7 are pivotally connected by a transverse shaft 11a with the depending rear extremities of heavy, forwardly extending arms 11 which are interconnected at their forward ends to form a subframe or yoke. The forward end of the

yoke so formed in the form of the invention shown in Figs. 1 to 4 inclusive, is supported upon two widely spaced sets of caster wheels 12, each pair of said wheels being journaled in a suitable bracket and each bracket having a centrally disposed king bolt 13 which is journaled in a socket provided by the interconnecting structure of the yoke.

The tracks are of conventional type comprising 10 endless traction elements 14 made up of the usual hinged links and trained about large driving sprockets 15 at the rear of the tracks and smaller idler sprockets 16 journaled on a transverse shaft 17 mounted in the forward portions of the track frame members 7. The track driving sprockets 15 are each independently driven through meshed gear connection between a gear 18 affixed to sleeve 19 upon which the driving sprockets 15 are secured, said gear 18 in each instance, being driven by a driving pinion 20 20 affixed to a transverse stub shaft 21 which is then driven, in the embodiment illustrated, by endless chain drive 22 from a transverse power take-off shaft 23 mounted in the upper and rear portion of the superframe attached to the rear portion 25 of the load-carrying body.

The forward end of the load-carrying body is 30 adjustably supported from the subframe or heavy forward yoke of the chassis through a pair of hydraulic jacks indicated as an entirety by the letter J, one disposed in upstanding position at each side of the machine and adjacent the forward portion of the load body and as shown having the cylinders thereof pivotally connected with the upper portion of the load body and having the hydraulic piston rods thereof pivotally connected at their lower ends with heavy, upstanding lugs 24 secured to the intermediate portions of the forwardly extending arms 11 of the subframe or yoke.

From the foregoing, it will be seen that the chassis of my machine is in the form of a vehicle supported at its rear portions by the two sets of cooperating tracks T and at its forward end ahead of the load-carrying body by the two sets of caster wheels 12. It further will be apparent that the load-carrying body of my machine is pivotally supported at its rear portion upon the rigid frame for the tracks and may bodily tilt upon the heavy, stationary axle 10 at the rear of the tracks and that adjustment of the forward end of the body relative to the ground or supporting surface may be made through operation of the hydraulic jacks J which connect the forward portion of the body with the forwardly extending, heavy arms 11 of the yoke.

Plow and combined elevator and creeper

The load accumulating body of my machine is of general box form, as will later be described in detail, and extends at least the full width of the chassis and preferably slightly beyond or in overhanging relation to the supporting tracks T. Both forward and rear ends of the body are open for receiving and progressively dumping and distributing material and the forward end of the body is provided with a plow of the scoop type extending across the entire forward end of the body and constituting an upwardly sloping and somewhat concave mold board 25 having a cutting edge 25a which preferably converges somewhat at the side portions of the mold board inwardly, as clearly shown in Fig. 1. Mold board 25 is secured in angled relation to the forward end of the load-carrying body and is

adapted to be adjusted in its cutting relation with the ground, through bodily tilting of the body upon the heavy, stationary axle 10 of the tracks through operation of the upstanding hydraulic jacks J. The cutting edge 25a is disposed rearwardly of the caster wheels 12, a sufficient distance for accommodation of a transversely disposed endless conveyor, indicated as an entirety by the letter C, which has the combined functions of serving as an elevating conveyor for material cut by the plow as well as an auxiliary traction-propelling device for the tracks T.

The endless conveyor C in the form illustrated, comprises a series (as shown, 3) of smaller endless sprocket chains 26 mounted in a triangulated rigid frame 27 which is pivoted at its upper and rearward end on heavy mountings to the forward end and upper portion of the load-carrying body at both of the sides thereof. The endless chains 26 are respectively trained about driving pinions 26a affixed to a transverse driving shaft 28 which serves as a pivotal connection of the frame and is journaled in heavy brackets or mountings, as previously described. The triangulated frame 27 has vertically disposed side portions rigidly interconnected and the outer ends of which have journaled transversely therebetween, idler rollers or sprockets 29 about which the lower and forward runs of the three chains are trained, holding and maintaining the chains 26 and the conveyor formed thereby, in the triangular relationship clearly illustrated in Fig. 2. Conveyor C in the form shown, is provided 35 with a plurality of cross slats 38 traversing and affixed in spaced relation to the chains 26 and forming earth-engaging cleats which, due to the driving of the conveyor in the direction indicated by the arrow in Fig. 2, causes cut soil to be engaged and elevated onto the forward end of the load-receiving body and which further engages the ground somewhat forwardly of the cutting of the plow, with tractive effort to produce a creeping action or auxiliary propulsion of the vehicle. While the scoop type plow itself is 40 adequate to, in the travel of the machine, lift cut material upon the bottom of the load body, with the assistance of conveyor C, material is more quickly elevated and may be accumulated to a stratum of considerable height, in fact, to the full height of the body.

Load-accumulating body and material distributing means

55 My load-accumulating body, indicated as an entirety by the letter B is of general, elongated box form comprising a pair of widely spaced vertical side walls 31, transversely and rigidly interconnected by suitable means and a bottom formed by an elongated endless apron 32, the upper run of which is supported upon a multiplicity of aligned transverse rollers 33 journaled between the side walls 31 of the body and disposed at the bottom thereof. Apron 32 may conveniently comprise a wire, relatively heavy rubber belt although of course, other suitable material may be utilized. The forward end of apron 32 is trained about an idler roller 34 disposed just rearwardly of the rear edge of mold board 25 60 while the rear of apron 32 is trained about a relatively large distributing roller which is journaled in the rear portions of the vertical walls 31 and is disposed with its upper periphery preferably slightly below the general level of the apron. 65 Roller 35, as shown, is driven from one of its

ends by endless chain drive 36, said driving chain being trained about a drive sprocket 37 affixed to a shaft 37a which is suitably driven from the motor or source of power. Guiding rollers 38 disposed in widely spaced relation engage the lower run of apron 32 to conform the same to the desired configuration and to serve as a belt-tightener. The driving means for load apron 32 may be reversible so that material may be progressively discharged and distributed from both the rear and the front ends of the load-accumulating body.

Power unit and driving connections

In the form of the invention illustrated, an internal combustion engine of suitable power or other power unit indicated as an entirety by the letter P, is mounted upon a superframe SF transversing and supported upon the reinforced upper edges of the vertical walls 34 of the load body with its power take-off shaft disposed, as shown, longitudinally of the body and at the rear of the motor. The propeller or power take-off shaft of the motor is connected with a torque converter unit indicated as an entirety by the letters TC disposed rearwardly of the motor and supported from the superframe SF. The torque converter is provided with a transversely disposed power take-off shaft 39 which traverses the load body and comprises two independently drivable sections 23 disposed at opposite sides of the longitudinal center line of the machine, each of said sections having an independent clutch mechanism 40 for connection with the power take-off of the torque converter. The outer ends of each of the driven transverse shaft sections 23 is provided with a heavy driving sprocket which, as shown, is connected for driving by the endless driving chain 22 with the appropriate stub shaft 21 which has fixed thereto, the pinion 20 for driving one of the tracks. The transverse power take-off shaft 39 also has beveled gear driving engagement with a central and longitudinally disposed driven shaft 42 which at its rear end is provided with a worm 42a meshed with a worm gear on a cross shaft 43 comprising the two drivable sections 37a which is connected by driving chains 36 with the driven larger roller 35 of the load-accumulating and discharge apron 32.

Coupled up with the torque converter and power take-off shaft is a reversing gear transmission mechanism 44 whereby power may be applied to the tracks for travel of the vehicle rearwardly. Power for driving the elevating and creeping conveyor C at the forward end of the machine is supplied through an elongated, longitudinally extending shaft 45 connected for driving at its forward end with the driven shaft 28 of the conveyor C. The rear end of the elongated shaft 45 is connected by beveled gears with a short cross shaft 46 which in turn, is driven at its inner end from a beveled driving gear 47 fixed to the longitudinally extending short shaft 42 which also drives the load-accumulating and discharging apron. A clutch mechanism 48 is interposed in shaft 46 controllable by the driver as will later be fully explained.

Driving controls

Selective application of power may be applied at will for driving the two sets of tracks in forward or reverse directions and for driving the elevating and creeping conveyor C as well as the load-accumulating and discharging apron 32. These controls are cooperatively related with the

operating mechanism of my machine in such manner that one operator may conveniently and easily control all operations and functions of the machine while observing both plowing and accumulation of load as well as the discharge and distribution of accumulated material.

To this end, in the embodiment of the invention illustrated, I provide a nearly horizontal cat walk W extending longitudinally of the machine 10 at the top of the superstructure and above the superframe and disposed at one side of the power unit and extending preferably to a point disposed, say 8 to 10 feet rearwardly of the front end of the box body. Right and left hand railings 50 and 51 are provided above and at the sides of cat walk W, said railings being supported in substantially horizontal position by upstanding standards 52 and being slidably mounted in bearing sleeves at the upper ends of said standards for restricted longitudinal movement therein to control respectively, the clutch mechanism 40 for the respective right and left hand set of tracks.

Mechanism is provided (not shown in detail) for shifting and controlling the clutch operation and 25 also transmission driving connections between each of the track driving shaft sections 23 and the source of power at the output of the torque converter TC. The shifting of gear driving connections and release and engagement of clutches 30 40 in each instance, is brought about by the shifting of one lever for each of the tracks. The lever for controlling the driving of the right hand track is connected by a link 50a which at its upper end is fixed to the rear end of the slide- 35 able railing 50. The lever for controlling the driving of the left hand track is connected by a link 51a with the left hand railing 51. Thus, the driver or operator from any point along cat walk W may longitudinally shift the railings 50 and 51 to cause both tracks to be driven in forwardly direction or to cause one track to be driven and the other idled to turn and guide the machine in its travel. Rearward pulling of 40 the railing members 50 and 51, at will controls 45 the reverse driving of the tracks, so that the machine may be as readily driven and controlled in rearward travel as in forward load-collecting travel.

To provide independent and immediately responsive driving controls for the combined elevator conveyor and creeper C and for the load-accumulating and discharge apron 32, elongated pedal strips 53 and 54 (see Fig. 3) are provided at the longitudinal sides of cat walk 50 W extending substantially the full length thereof. The pedal strip 53 for controlling the driving of conveyor C is affixed to the upper ends of rocker arms 53a which in turn are fixed to an elongated tube 53b positioned below and longitudinally of the cat walk W. The tube 53b at its rearward end is operatively connected with clutch or gear shift mechanism 48 for drivably connecting the short drive shaft 46 for conveyor C with the source of driving power. Thus, when pedal strip 53 is depressed, conveyor C will be driven.

Pedal strip 54 is affixed at its ends to the upstanding rocker arm 54a which are in turn affixed to the ends of a shaft 54b, said shaft being telescoped as shown within the tube 53b and extending rearwardly beyond clutch 48 and connected by linkage with a clutch 55 for controlling the driving of the large distributing roller 35 over which the load-accumulating and discharge apron 32 is trained. Thus, when pedal strip 54

is depressed, driving connection between the source of power and load-accumulating and discharging apron is instantly effected.

Other controls (not shown) such as throttle lever and other motor controls, are conveniently mounted for availability of the operator upon or adjacent the cat walk.

Reversible scraper blade

A scraper mold board 56 is supported from a 10 depending, vertically adjustable turntable bracket 57 of conventional form (details not shown) near the rear end of the load body being of the general type used on patrol graders whereby in the full line position, it may be angularly adjusted 15 to ploy material discharged by apron 32 to either right or left sides of the grade when the machine is driven rearwardly. The mold board may be reversed as shown in dotted lines, to scrape 20 and level when the machine is driven forwardly.

Operation

My machine, in its entirety, comprises a full road building unit adapted to do the combined work of steam or power shovels, elevator graders, 25 dump wagons, bulldozers and patrol graders. To cut or grade and simultaneously accumulate a load, the hydraulic jacks J are adjusted to maintain the cutting edge 25a of the plow at the desired level below the surface of the ground. The machine is then driven in a forwardly direction and from the cat walk the operator depresses 30 pedal strip 53 to operate the forward conveyor C, this conveyor serving to assist the plow in the elevation of the soil cut and to lift the same and accumulate the load progressively upon the forward end of the load-accumulating apron 32. From time to time, or constantly during plowing 35 when the stratum cut is deep, apron 32 is driven in a rearwardly direction and may thus be loaded to its full capacity if desired. Since the rigid triangulated frame 21 for conveyor C is pivotally mounted at its upper end, it will adjust itself in proper spaced relation to the cutting edge of the plow to engage the surface of the ground and produce a creeping action as well as elevating the material cut upon the apron 32. The control pedals 53 and 54 are returned to normal, inoperative position by any suitable mechanism, 40 not shown, provided inherently in conventional clutch mechanism.

Collected material may be progressively distributed from the rear end of the load body B either in forward or rearward travel of my machine for filling purposes. This is subject to the instant control of the operator through the pedal strip 54 in its connection with the clutch mechanism for connecting the driving of the large rear distributing roller 35.

It will be noted that material is cut, accumulated and subsequently discharged throughout the full width of the machine with the simplification of chassis and working mechanism. In leveling roads and building sites, the operation of my machine may be substantially continuous. It is not necessary to turn the machine for obtaining a new load since load is accumulated in forward travel and may be distributed at will, for filling. In the filling of very low spots, the loaded machine may be driven rearwardly and dirt discharged and spread evenly or as desired, ahead of their tracks in rearward movement to support the machine partially upon the material distributed. Likewise, material may be discharged from the front or plow-equipped end of the load body, by reversing the driving of the

apron and adjusting the height of the plow for operation by the hydraulic jacks J.

In the form of the invention illustrated in Figs. 1 to 4 inclusive, the depth of the plow is adjusted by bodily tilting the load-carrying body upon the large, stationary axle of the tracks through operation of the jacks J.

The combinative relationship of my controls for driving of the tracks as well as operation of the conveyor C and apron 32 enables a single operator to drive and operate the machine from any point along the cat walk W at the top of the load body. From this cat walk, the operator may observe the conditions at both forward and rear ends of the machine.

When the machine, with an accumulated load, is driven rearwardly, material in stratum form may be discharged to fill cuts in advance of the tracks T whereby this material may be packed by the subsequent travel of the very wide tracks thereover.

Embodiment of Figure 5

In Fig. 5, the forward end of a somewhat different form of the invention is illustrated, having a load-accumulating body B of the form of the invention previously described with a similar plow 25 attached to the forward end of the body. The load-accumulating and discharge apron 32 is also similar to that of the form illustrated in Fig. 1 to Fig. 4 and the rear of the load-carrying body is mounted on rearwardly disposed tracks T similar to that of the form first described.

In the form of the invention of Fig. 5, however, 35 the front end of the vehicle and the body B is wholly supported by the creeper and elevator mechanism indicated as an entirety by the letter M. This mechanism is generally similar per se to the conveyor mechanism C of the form first described, comprising a triangulated frame 58 in which are journaled the top and rearward driving sprockets 59 about which the endless chains 60 are trained and in which frame the idler rollers 61 are also journaled at the lower and forward portion thereof. The triangulated frame 58 is held and maintained rigidly in a desired, adjusted relationship with reference to the bottom of the load-carrying body B by means of hydraulic jack mechanisms 62, one disposed at each side of the body and interposed between the lower forward portion of the body and the intermediate portion 40 of the sides of triangulated frame 58. The horizontal forward portion of the conveyor and creeper mechanism M engages the ground and the forward end of the vehicle and body is thus supported. The adjustment of hydraulic jack 45 62 changes the relationship between the plow and the supporting structure for the front end of the body and thus, determines the depth of the cut.

For this last mentioned form of the invention, 50 the caster wheels at the front of the vehicle are eliminated as well as the forwardly extending subframe or yoke of the form first described and the over-all length of the machine is decreased and greater tractive effort or creeping action is obtained than in the form first described.

From the foregoing description, it will be seen that I have provided a simplified, highly efficient earth moving machine for building roads and leveling and excavating building sites and the like, adapted to do the work of power shovels, graders, dump wagons, plows, bulldozers, scrapers and self-contained, self-propelled and capable of being operated by one person.

It will of course, be understood that various 55 changes may be made in the form, details, ar-

angement and proportions of the parts without departing from the scope of my invention.

What I claim is:

1. An earth-moving and distributing machine having in combination transversely spaced sets of power driven, ground-engaging propelling and supporting mechanisms, a substantially horizontal frame supported mainly from said mechanisms and extending medially thereof longitudinally of the machine and having its forward end disposed far ahead of said mechanisms, a load-accumulating body supported on said frame and extending longitudinally thereof and having driven conveyor mechanism at the bottom thereof, the forward end of said body being disposed far ahead of said ground-engaging supporting mechanism, earth-cutting mechanism connected with the forward end of said frame and adapted to cut earth in the travel of said machine substantially the full width of said body and immediately ahead of the forward end of said body, a soil-elevating and moving conveyor mounted above said earth-cutting mechanism and extending forwardly thereof and consisting of a triangulated conveyor frame having an endless conveyor trained in triangulated form thereon and provided with a substantially horizontal forward run adapted to engage the ground and assist in the tractive effort of said machine and having an upwardly and rearwardly inclined run extending from said forward run for moving cut earth upwardly and rearwardly upon the receiving, forward end of said load-accumulating body and power driving connections for said last mentioned conveyor.

2. An earth-moving and distributing machine having in combination spaced sets of driven ground-engaging, propelling and supporting mechanisms, a low, substantially horizontal frame supported mainly from said mechanisms and extending medially therebetween and having its forward end disposed far ahead of said mechanisms, a load-accumulating body supported medially on said frame and extending longitudinally thereof and having an elongated and continuous material-accumulating conveyor forming the bottom thereof, said conveyor extending at its forward end ahead of said ground-engaging supporting mechanism, means for tilting said conveyor on an axis transversely of said frame to dispose the forward end thereof some distance below the ground line and to also elevate said forward end to a position well above the ground line, means for driving said conveyor, earth-cutting mechanism connected with the forward end of said frame and adapted to cut earth substantially the full width of said conveyor, said mechanism being mounted at the forward end of said conveyor and movable with said conveyor for tilting adjustment therewith, a soil-elevating and moving conveyor mounted above said earth-cutting mechanism and extending forwardly thereof and consisting of a suspended triangulated conveyor frame having an endless conveyor trained in triangulated form thereon and provided with a substantially horizontal forward run adapted to engage the ground and assist in the tractive effort of said machine and having an upwardly inclined run disposed rearwardly

of said forward run for moving cut earth upwardly and rearwardly upon the receiving end of said material-accumulating conveyor and power driving connections for said last mentioned conveyor.

3. An earth-moving and distributing machine having in combination a pair of endless, driven tracks for supporting and propelling the machine over the ground, a low, substantially horizontal frame supported mainly from said tracks and having its forward end disposed far ahead of said tracks, wheels in the forward end of said frame for partially supporting said frame, a load-accumulating body supported on said frame and having an instantly controllable elongated and continuous material-accumulating and moving conveyor forming the bottom thereof, said conveyor lying throughout substantially in a common plane and extending at its forward end far ahead of said tracks and behind said wheels and extending at its rear end some distance behind said tracks, means for tilting said conveyor longitudinally of said machine to dispose the forward end thereof some distance below the ground line and to also elevate said forward end to a position well above the ground line, means for driving said conveyor both forwardly and rearwardly, an earth-cutting element mounted and positioned to cut and deliver earth to the full width of said conveyor mounted in advance of the forward end thereof, a soil-elevating and moving conveyor mounted above said earth cutting mechanism and extending forwardly thereof and consisting of a suspended vertically adjustable, endless conveyor having a substantially horizontal run mounted to assist in the forward support of said frame and adapted from above to engage and move cut earth upwardly and rearwardly into the receiving end of said load carrying body, a motor mounted on said frame and having driving connections with said tracks for propelling the machine over the ground and having other driving connections with said earth elevating conveyor for causing the lower run of said conveyor to travel rearwardly and mechanism for adjustably and fixedly connecting said earth elevating mechanism in several relations with the forward end of said frame to assist in the support and propulsion of the same.

50 HANS R. MILLER.
